United States Patent Office

Des. 201,998
Patented Aug. 17, 1965

201,998

BOTTLE OR SIMILAR ARTICLE

Tage Kay Kirsby, Birkerod, Denmark, assignor to Colgate-Palmolive Company, New York, N.Y., a corporation of Delaware

Filed June 24, 1964, Ser. No. 82,444

Claims priority, application Republic of South Africa
Dec. 27, 1963

Term of patent 14 years

(Cl. D58—6)

FIG. 1 is a top plan view of a bottle or similar article embodying my new design;

FIG. 2 is a bottom plan view thereof;

FIG. 3 is a front elevational view thereof;

FIG. 4 is a back elevational view thereof;

FIG. 5 is a side elevational view thereof; and

FIG. 6 is a side elevational view of the side opposite that shown in FIG. 5.

I claim:

The ornamental design for a bottle or similar article, as shown.
